UNITED STATES PATENT OFFICE.

ALBERT S. HOWELL, OF CHICAGO, ILLINOIS, ASSIGNOR TO BELL & HOWELL COMPANY, OF CHICAGO, ILLINOIS, A CORPORATION OF ILLINOIS.

STOP MECHANISM FOR FILM-PERFORATORS AND OTHER APPARATUS.

1,262,671.

Specification of Letters Patent. Patented Apr. 16, 1918.

Application filed March 2, 1917. Serial No. 152,011.

To all whom it may concern:

Be it known that I, ALBERT S. HOWELL, a citizen of the United States, and a resident of the city of Chicago, county of Cook, and State of Illinois, have invented certain new and useful Improvements in Stop Mechanism for Film-Perforators and other Apparatus, of which the following is a specification.

- 10 In the handling of cinematographic film for use in projecting apparatus, it is imperative that considerable care be exercised until the film has passed through the final process of printing and developing the strips. All
15 operations in the divers processes are usually performed in a dark room where the illumination is by means of a nonactinic and subdued light, and consequently most of the apparatus for performing these operations
20 must be capable of automatically stopping at desired and predetermined points and without the liability of spoiling any portions of the film strips. It is with this in view that I have designed the hereinafter
25 described stop mechanism that is adapted to be installed upon suitable apparatus employed in the handling of cinematographic film.

More particularly my invention relates to
30 an automatic stop mechanism for use upon film perforating apparatus, such as is disclosed in my copending application for Letters Patent of the United States, filed March 2, 1917, Serial No. 152,009 for an "Automatic film perforator," and its companion application, filed March 2, 1917, Serial No. 152,010, for a "Bed or table for film perforators," to both of which reference is here made for an understanding of the adaptability of my present invention, although it
40 will be understood the stop mechanism is capable of use on other apparatus.

Among the objects of my invention is the provision of a stop mechanism that is capable of adjustment in order that the devices for actuating the punches may be stopped instantly upon the end of the strip of film being reached; to provide an indicator or alarm that will notify the operator
50 or attendant as soon as the end of the film

strip is reached, so that a new strip may be inserted for perforation; and to provide a device of this character that is dependable in its operation, simple in its construction, and economical to manufacture, and having a maximum of efficiency with a minimum of parts.

I prefer to accomplish the divers objects of my invention substantially by the means and in the manner hereinafter fully described and as more particularly pointed out in the claims, reference being had to the accompanying drawings forming a part of this specification in which,—

Figure 1 is a side elevation of my stop mechanism shown attached to a perforating machine adjacent a film supply spool, illustrating the relative position of the parts when the machine is stopped.

Fig. 2 is a similar view showing the parts in their relative adjusted position during the operation of the machine, the film engaging arm, however, being raised to a vertical position.

Fig. 3 is a top plan of the structure shown in Figs. 1 and 2.

Fig. 4 is a view of a fragmentary portion of a film spool and disk, illustrating the relation of the film engaging arm with respect to the film strip.

Fig. 5 is a detail view of the element for actuating the switch plunger.

In the drawings similar reference characters are employed to designate the same parts throughout the divers figures thereof.

Referring more particularly to Figs. 1, 2, and 3 of the drawings, 10 represents the supporting frame that is preferably provided with an arm 11 in the outer end of which latter a spindle 12 is mounted and to one face of which a disk 13 is secured to afford respectively an arbor and a guide for a spool of film 14. The core 15 of the spool of film is inserted on the spindle 12 in the usual manner so that the edge of the film wound upon the same will contact the adjacent surface of disk 13.

Suitable hollow bearing bosses 16 and 17, projecting from opposite sides of frame 10, provide means for journaling a short rock 100

shaft 18, one end whereof projects beyond the end of bearing 17 and has the adjacent end of an arm 19 secured thereto. The opposite end of this arm 19 terminates at a 5 point adjacent stud 12 and has a film engaging roller 20 journaled laterally thereon. This roller is of the ordinary spool type in order that only the margins of the film on spindle 12 will be engaged thereby and has a 10 relatively wide flange 21, that is adapted to rest against the edges of the coiled film on said spindle opposite disk 13.

The opposite end of rock-shaft 18 extends through bearing 16 and has a sleeve 22 mounted thereon and keyed thereto so as to be moved simultaneously with said rock-shaft and arm. A short arm or embossment 23 extends from one side of sleeve 22 and a pin 24 projects outwardly from said 20 embossment in a horizontal plane above the horizontal plane of the axis of rock-shaft 18. This pin is so disposed as to have one end of a coiled contraction spring 25 secured thereto and the opposite end of said 25 spring is secured to the outer end of a stud 26 projecting from the upper edge of the lateral arm 11 of the frame, the tension exerted by said spring being adapted to rock the shaft 18 so as to press the roller 30 20 down against the film on the spool. The disposition of the spring 25 is such that when shaft 18 is rocked sufficiently to cause the pin 24 to pass the dead center with respect to the rock-shaft and stud 26, the 35 arm 19 will be moved to and retained in a substantially vertical position, as shown in Fig. 2 of the drawings.

Secured to the frame below shaft 18 is a suitable electric switch 27 of the "snap" 40 type, that is inclosed within a boxlike housing 28 that is provided in its upper wall with an opening 29, through which the operating button 30 of said switch projects, while the circuit wires 31, 31 leading to 45 and from said switch pass through insulating bushings 32, 32 in the opposite wall of said housing. An operating plunger 33 for said switch button is reciprocally mounted in suitable vertically alining bored brackets 50 34, 34, projecting laterally from the frame 10 above said housing, and the lower end of said plunger is provided with a downwardly projecting slotted plate 35 that connects the switch button with said plunger 55 and permits the switch to be actuated by said plunger. The upper portion of the plunger extends above its upper bracket and is knurled or milled to provide a hand grasp 36, while intermediate the brackets 60 said plunger is provided with a longitudinally elongated slot 37, in which a small anti-friction disk or roller 38 is journaled. Loosely mounted upon rock-shaft 18 between bearing 16 and the adjacent end of

sleeve 22, is a trigger that preferably consists of a suitably shaped disk 39 that is provided with a pair of fingers 40, 40, that extend into the slot 37 in the plunger and engage opposite segments of the anti-friction disk 38, and is also provided with a 70 single finger 41, the object whereof will be later described.

Carried by the embossment 23, on sleeve 22, is a hollow barrel 42, in which a threaded bolt 44 is disposed so that its enlarged 75 or conical shaped head 43 projects out of the end of the bore of said barrel adjacent the finger 41, and is adapted to engage the latter. A coiled spring 46 is adapted to be compressed between said head 43 and the 80 opposite end of the bore of said barrel, and a lock nut 45 is mounted upon the extended threaded end of the bolt 44 to prevent its accidental rotation, the adjustment of said bolt being for the purpose of regulating the 85 relative movement of the rock-shaft and disk 39 with respect to the moment of the snapping of the switch 27 by the plunger, and it is preferably "set" to such a position that when the last coils of film are leaving 90 the spool, the switch will be actuated to cut out the motor that drives the apparatus.

The operation is substantially as follows:—When a spool of film is to be placed upon spindle 12, the contact roller 20 and 95 its arm 19 are raised so that the spring 25 will hold them in an elevated or vertical position (Fig. 2), and after the spool has been positioned, said arm is lowered until the roller engages and rests upon an upper 100 segment of the roll of film. The plunger 33 is now raised by its hand grasp 36, thus opening the switch and permitting the motor to actuate the drive shaft or other operating mechanism it is adapted to drive, 105 and it will be seen that this movement of plunger 33 will cause the disk 39 to be moved upwardly until its finger 41 is in close proximity to the conical head 43 of bolt 44, providing the necessary adjustment 110 of the latter has been made. The operating mechanism withdraws film from the roll constantly reducing the diameter of the latter and causing the roller 20 and its 115 shaft 18 rocked, which latter will move the bolt head 43 against the finger 41 of disk 39, and thereby, through the upper one of the pair of fingers 40, push down the plunger 33. Proper adjustment having been 120 made to the bolt 44, it will be found that when the final or innermost coil of the roll of film is unwound from the spool, the plunger will have been moved downwardly a distance sufficient to force the switch to 125 snap and cut off the current, thereby stopping the motor. This snapping of the switch will give the plunger a jerk, thereby

causing a spring or wire 47, disposed laterally thereon to vibrate to such an extent that the weight or striker 48 on the full end thereof will sound an alarm bell 49, 5 conveniently mounted adjacent the same, thus notifying the operator of the stoppage of that particular machine.

While I have herein described and illustrated certain specific means for carrying out my invention, it will be obvious to others skilled in the art of my invention, that divers modifications or refinements may be made thereto without materially departing from the spirit of my invention. 10 I desire it to be understood that all such changes are contemplated as included within the scope of my invention as expressed in the appended claims.

What I claim as new is:—

20 1. Stop mechanism comprising a switch, a reciprocable member adapted to operate the same, and devices for actuating said member consisting of a rocking element, a gravity operated arm connected to said element, and a roll of film supporting the free end of said arm, the unwinding of said roll adapted to change the relative position of said arm whereby said member is reciprocated to operate said switch.

25 2. Stop mechanism comprising a switch, a reciprocable plunger adapted to operate the same, a rock-shaft, a device mounted on said shaft and adapted to coöperate with said plunger, an arm secured to said rock-shaft, and a roll of film supporting the free end of said arm the unwinding of which is adapted to change the relative position of said arm whereby said device is moved to reciprocate said switch operating plunger.

30 3. Stop mechanism comprising a switch, a reciprocable plunger adapted to operate the same, a rock shaft, a device coöoperating with said plunger, and means carried by said rock-shaft for causing a coöperation 45 between said device and said rock-shaft, one member whereof coöperates with a roll of film whereby the unwinding of said roll causes a movement of said shaft which movement is transmitted to said switch operating plunger.

35 4. The combination with an arbor adapted to receive a roll of film, of a switch, and means for actuating said switch consisting of a reciprocable member, a rock-shaft, a pivoted device movable with said reciprocable member, an arm mounted on said rock-shaft the free end whereof moves with respect to said film and is controlled thereby, and means operatively connecting said 50 shaft and said pivoted device whereby when said arm has reached a predetermined position said device will actuate said member and cause said switch to be operated.

5. The combination with an arbor adapt-

ed to receive a roll of film, of a switch, and 65 means for actuating said switch consisting of a reciprocable plunger, a rock-shaft, a trigger coöperating with said plunger, an arm mounted on said rock-shaft the free 70 end whereof moves with respect to said film and is controlled thereby, and an adjustable device carried by said rock-shaft and adapted to engage said trigger and thereby actuate said plunger.

6. Mechanism of the kind described comprising a film holding arbor, a pivoted film engaging arm, a trigger-piece pivoted adjacent said arm, means carried by said arm for engaging said trigger, and a switch operating member adapted to be engaged by 80 said trigger and actuated thereby.

7. Mechanism of the kind described comprising a film holding arbor, a pivoted film engaging arm, a spring adapted to hold said arm yieldingly in coaction with said film, a 85 trigger-piece, means carried by said arm for engaging said trigger, and a switch operating member adapted to be engaged by said trigger and actuated thereby.

8. Mechanism of the kind described comprising a film holding arbor, a pivoted film engaging arm, a trigger-piece rotatably mounted upon the pivot of said arm, means carried by said arm for engaging said trigger, and a switch operating member adapted to be engaged by 90 said trigger and actuated thereby.

9. Mechanism of the kind described comprising a film holding arbor, a pivoted film engaging arm, a trigger-piece, adjustable 100 means carried by said arm for engaging said trigger, and a switch operating member adapted to be engaged by said trigger and actuated thereby.

10. Mechanism of the kind described comprising a film holding arbor, a pivoted film engaging arm, a spring adapted to hold said arm yieldingly in coaction with said film, a trigger-piece rotatably mounted upon the pivot of said arm, adjustable means actuated by said arm for engaging the trigger, and a switch operating rod adapted to be engaged by 110 said trigger and actuated thereby.

11. Stop mechanism comprising a switch, 115 a reciprocable plunger adapted to operate the same, a rock-shaft, a trigger loosely mounted on said shaft and adapted to co-operate with said plunger, an arm secured to said shaft the free end whereof rests 120 upon the outer coil of a roll of film and is controlled thereby, and an adjustable device carried by said rock-shaft and adapted to actuate said trigger.

12. Stop mechanism comprising a switch, 125 a reciprocable plunger adapted to operate the same, a rock-shaft, a trigger loosely mounted on said shaft and adapted to co-

operate with said plunger, an arm secured to said shaft the free end whereof rests upon the outer coil of a roll of film and is controlled thereby, a sleeve secured to said rock-shaft, and an adjustable bolt mounted on said sleeve one end whereof is adapted to engage and actuate said trigger.

Signed at Chicago, county of Cook and State of Illinois, this 27th day of February, 1917.

ALBERT S. HOWELL.
